UNITED STATES PATENT OFFICE.

WILLIAM J. GAGNON, OF BRIDGEPORT, CONNECTICUT, ASSIGNOR TO THE BEAD CHAIN MANUFACTURING COMPANY, OF BRIDGEPORT, CONNECTICUT, A CORPORATION OF CONNECTICUT.

ELECTRICAL CONNECTER.

Original application filed February 29, 1924, Serial No. 695,972. Divided and this application filed October 14, 1925. Serial No. 62,481.

Reference may be had to the accompanying drawings, and the reference characters marked thereon, which form a part of this specification. Similar characters refer to 5 similar parts in the several figures therein.

This application is a division of an application filed by me February 29, 1924, Serial No. 695,972, for electrical connectors.

The principal object of the invention is to 10 obtain a more effective engagement between the cooperating contact portions of the connector.

Other objects will appear in connection 15 with the following description.

Fig. 1 of the drawings is a view in side elevation of a socket-member of an electrical connector with the housing partly broken-away to expose to view the two contact-sockets which are made in accordance with 20 my invention.

Fig. 2 is a vertical cross-section of a broken-away portion of the plug-member of the connector, showing in side elevation the two plugs, and illustrating diagrammatically 25 a resistance included in the circuit between the plugs.

Fig. 3 is a horizontal section of the socket-member taken on the broken line 3—3 in Fig. 1.

Fig. 4 is a view in side elevation on an enlarged scale of one of the contact sockets as shown in Fig. 1.

Fig. 5 is a horizontal section on an enlarged scale taken on the broken line 5—5 35 in Fig. 2, through one of the contact-plugs and the plug-enclosing contact-socket.

Referring to the drawings wherein the invention is shown in preferred form, I have shown the socket-member, 1, provided with 40 two contact-sockets, 3, and the plug-member, 2, provided with two plugs, 4, although my invention is equally applicable to a single contact-socket, 3, and a single plug, 4.

In the drawings I have shown the invention applied to an electrical connector as used 45 for ordinary household devices such as toasters, coffee percolators, electric flat-irons and the like, in which case a plurality of contact-sockets and plugs are employed, the plug-member, 2, being the device to be heated by means of a resistance, 5, included in the circuit between the plugs, 4.

I preferably make the plug in the form of a hollow post, split longitudinally along

one side as shown at 6; and form the wall of 55 the plug of two metals, 7 and 8, of split cylindrical form welded or otherwise secured together, the inner member, 8, having a higher coefficient of expansion than the outer member, 7, whereby under the action of heat 60 the post tends to expand or increase in diameter. The plug may be made solid if preferred.

In applying my invention to a contact-socket, 3, I form the socket of two complementary members, 3^a and 3^b, each in an arc of a circle in cross-section and adapted to present concaved or cylindrical surfaces to the inserted plug.

These concaved surfaces are preferably 70 formed by indent longitudinal edge portions of the body of the respective socket-members as shown; but they may be formed in any other known manner.

The two socket-members are connected 75 together by means of a binding-screw, 5, which also serves as a means for connecting a line-wire with the contact-socket.

The connected-together socket-members are adapted to receive between them a contact-plug, 4.

Each socket-member, 3^a and 3^b, is composed of two metals welded or otherwise secured together, the outer metal, 3^c, having a higher coefficient of expansion than the 85 inner metal, 3^a.

Each socket-member thus includes a thermostatic member tending under the action of heat to contract the member and thus to reduce the radius of the arc of its plug-engaging surface.

The operation of the device is as follows:

A plug, 4, is inserted in a socket, 3, they being made to approximately fit together with the socket of normal diameter. When the electric current is transmitted between the contact-socket, 3, and the plug, 4, if the plug does not fit sufficiently tightly within the contact-socket, the socket and plug become heated, causing the plug to tend to expand and the contact-socket members to tend to contract, due to their respective 90 thermostatic constructions.

The split portion of the wall of the plug thus tends to move under the action of heat toward the wall of the cooperative contact-socket; and in a similar manner the walls of the contact-socket under the action of heat 100

tend to move toward the cooperative contact-plug.

Any looseness in the fitting of the plug within the contact-socket is thus automatically corrected in the operation of the device.

In the use of electrical connectors of the type to which this invention is particularly applicable, there is a tendency for the resili-
10 ent and tempered parts to become annealed under the action of great heat developed in the use of the electrically heated device to which the electric current is supplied through the connector, resulting in loose
15 contacts and resultant arcing between contact-surfaces which should be in close contact with each other.

My invention tends to overcome this difficulty by automatically increasing the pressure
20 between contacting surfaces as the temperature of the connector parts increases.

I do not wish to be limited to the constructions shown and above described, as, for certain purposes of the invention, various
25 changes may be made in the form and arrangement of various parts of the device without departing from the spirit of the invention.

It will also be understood that claims to
30 patentable features of the connector illustrated, broader than those appended hereto, are not waived. Such generic claims are

presented in the aforesaid original application Serial Number 695,972, and one or more of the other divisional cases thereof hereto-
35 fore filed.

What I claim as new and desire to secure by Letters Patent is—

1. A connector for electrical conductors including a contact-socket formed of two cooperative arc-shaped members adapted to engage an inserted contact-plug, one of said members having a thermostatic element tending under the action of heat to reduce the radius of its arc.
40

2. A connector for electrical conductors including a contact-socket formed of two cooperative arc-shaped members adapted to engage an inserted contact-plug, each of said members having a thermostatic element tending under the action of heat to
45 reduce the radius of its arc.

3. A connector for electrical conductors including a contact-socket formed of two cooperative arc-shaped members secured together at their inner ends and adapted to engage an inserted contact-plug, one of said members having a thermostatic element tending under the action of heat to reduce the radius of its arc.
55

In testimony whereof, I have hereunto set my hand this 28th day of September, 1925.

WILLIAM J. GAGNON.
